UNITED STATES PATENT OFFICE.

DOCTOR FRANKLIN MORGAN, OF CHICAGO, ILLINOIS.

DAMPER-REGULATOR.

No. 840,644.

Specification of Letters Patent.

Patented Jan. 8, 1907.

Application filed April 27, 1905. Serial No. 257,749.

To all whom it may concern:

Be it known that I, DOCTOR FRANKLIN MORGAN, a citizen of the United States, residing at Chicago, in the county of Cook and State of Illinois, have invented certain new and useful Improvements in Damper-Regulators, of which the following, when taken in connection with the drawings accompanying and forming a part hereof, is a full and complete description, sufficient to enable those skilled in the art to which it pertains to understand, make, and use the same.

The object of this invention is to obtain an apparatus by means of which a determined variation in temperature of a confined body of air will produce movement of a piston or connecting rod, and thereby perform desired work, while at the same time means are provided so that if any considerable quantity of such air escapes from the confining vessel when the temperature thereof is raised and the pressure thereof is above atmospheric pressure additional air will be automatically supplied to such vessel when the same is at atmospheric temperature, thereby insuring continuous and uniform operation of the apparatus.

A further object of this invention is to obtain an apparatus of which the operation will be uniform.

Figure 1 of the drawings referred to as forming a part of this specification illustrates an apparatus embodying this invention in vertical sectional view with an elevation of the front of a heating apparatus and with a connection between the apparatus embodying this invention and the damper of the heating apparatus. Fig. 2 is an elevation of a boiler, a steam-supply pipe therefrom, a return-pipe to discharge the water of condensation back to the boiler, and an apparatus embodying this invention attached to such return-pipe; and Fig. 3 is a vertical sectional view of the mechanism whereby the maximum pressure in the closed cylinder of the apparatus is determined and additional air is supplied to such cylinder when required while the cylinder and contents are in a cooled condition.

A is a cylinder closed at the upper end by the head *a* and at the lower end by a movable wall in base *B*. Base *B* consists of the parts *b b'*. *C* is a diaphragm forming a movable wall secured in place between such parts *b b'*. Parts *b b'* are respectively provided with apertures therein. Such aperture in part *b*

is lettered *D* and serves as a passage through which water or other liquid (lettered *F*) may flow from cylinder *A* into the space between *b b'* of the head *B* and in contact with dia- 60 phragm *C*.

F is a lever pivotally mounted on fulcrum *f*.

G is a connection between lever *F* and the under side of diaphragm *C*. 65

g is a pin in connection *G*, against the under side of which the lever *F* is held by weight *H*. Weight *H* is adjustable on the lever *F*.

I is a pipe connected, by means of pipe *J*, to the steam-supply of the heating system in 70 which this apparatus is placed, and *K* is a steam-discharge pipe connected to the lower end of pipe *I*.

L is an ordinary venting-valve attached to pipe *K* by pipe *l* and permitting air to flow 75 therethrough from pipe *K*, while preventing water of condensation or steam to any considerable amount flowing therethrough.

M is the discharge-pipe of venting-valve *L*.

When the apparatus embodying this in- 80 vention is attached to a steam-heating device wherein an exhaust-pump is used, the pipe *M* may be attached to the exhaust side of such pump, while in other vacuum steam-heating systems such pipe *m* may be connected 85 to the air-eduction pipe.

N is a closed cup arranged to hold mer- 90 cury or other liquid, and *O* is a pipe establishing communication between the cup *N* and the interior of cylinder *A*.

P is a vertical pipe communicating with the cup *N* at its lower end and open into the cup *Q* at its upper end. Cup *Q* is open to the atmosphere.

R is a flexible cord attached to lever *F* at 95 one end and extending from thence over the pulleys *S S* and attached at its other end to damper *T* of the steam-generator *U*, as at *t*.

The apparatus is shown in the drawings with the air which constitutes the expandible 100 member operating the device and which is contained in cylinder *A* expanded so that the damper is closed. At such time the expansion of the air forces the liquid *E* against dia- 105 phragm *C* and also forces the mercury con- tained in cup *N* into pipe *P* until a sufficient quantity of such mercury is in such pipe *P* (as *V*) to balance the pressure in cylinder *A*. If the pressure in cylinder *A* is sufficient, all the mercury in cup *N* may be contained in pipe *P* 110 and cup *Q*, and any additional pressure in cylinder *A* will force some of the heated air

therein underneath the mercury in pipe P, whereupon such air will rise through the mercury and escape to the atmosphere.

When the contents of the cylinder A are cooled and the pressure in such cylinder thereby reduced, mercury in pipe P will flow into cup N therefrom, and in case any heated air from the cylinder has escaped through pipe P, as above described, additional air will flow into the cylinder A to replenish such cylinder.

The air constituting the expandible member of this apparatus in cylinder A is warmed by steam or water of condensation flowing through pipe I. In case air is contained in pipe I when steam or water of condensation enters such pipe through pipe J, such air will flow into pipe I through venting-valve L and into pipe M. The venting-valve L is supplied to prevent the trapping of air in pipe I, as might occur if the end of pipe K were closed by water of condensation.

Liquid E is used to prevent the heated air of cylinder A coming in contact with diaphragm C.

In the operation of this apparatus steam in pipe I heats the air in cylinder A. When the heated air forming the expandible member in cylinder A cools, as by the cooling of the contents of pipe I and the radiation of heat from cylinder A, such air contracts, the pressure thereof on liquid E is thereby lessened, and the weight H on lever F will turn such lever on fulcrum f to raise connection G and diaphragm C and also to raise damper T of steam-generator U.

The pipe P is of sufficient height to hold a column of liquid requiring a pressure to sustain it equal to the pressure desired in cylinder A when the air therein is heated. Hence when water is substituted for mercury V as the liquid therein (as it may be) the pipe P must be at least, say, thirteen and six-tenths times as long as it is when mercury is used, and cup N must be proportionately large.

Having thus described my invention, what I claim as new, and desire to secure by Letters Patent, is—

1. A receptacle provided with a movable

wall, means to automatically limit pressure of heated air in the receptacle, and to automatically replenish, when the air in the receptacle is cooled, air forced from the receptacle when heated, means to raise the temperature of the air in the receptacle to above climatic temperature, a damper, a fulcrumed lever, a connection between the lever and the damper and a connection between the lever and the movable wall and means to vary the pressure of the connection against such movable wall.

2. A receptacle provided with a movable wall, means to limit pressure of heated air in the receptacle, and to automatically replenish, when the air in the receptacle is cooled, air forced from the receptacle when heated, a pipe to convey heating fluid, such pipe extending through the wall of the casing thereinto and therefrom and means to vent such pipe of the air contained therein, a fulcrumed lever, a connection between the lever and the movable wall, and means to vary the pressure of such connection against the movable wall.

3. The combination of a two-part base, each part provided with a hole therethrough, with a diaphragm secured between the parts, a cylinder closed at its upper end attached to the upper one of the parts, such cylinder arranged to hold liquid and air, a pipe for heating fluid extending through the side wall of the cylinder into and out thereof above the liquid therein to control the temperature of the air contained in such cylinder, a seal, and a communicating way between the seal and the interior of the cylinder.

4. The combination of a two-part base, each part provided with a hole therethrough, with a diaphragm secured between the parts, a cylinder closed at its upper end attached to the upper one of the parts, such cylinder arranged to hold liquid and air, and a pipe for heating fluid extending to and connected with the cylinder above the liquid therein to control the temperature of the air contained in such cylinder.

DOCTOR FRANKLIN MORGAN.

In presence of—

CHARLES TURNER BROWN,
CORA A. ADAMS.
